UNITED STATES PATENT OFFICE.

HERMAN L. GREVE, OF NEW YORK, N. Y.

MAILING-WRAPPER.

1,092,210.

Specification of Letters Patent.

Patented Apr. 7, 1914.

Application filed April 17, 1913. Serial No. 761,713.

To all whom it may concern:

Be it known that I, HERMAN L. GREVE, a citizen of the United States, and a resident of New York city, borough of Brooklyn, in the county of Kings and State of New York, have invented certain new and useful Improvements in Mailing-Wrappers, of which the following is a specification.

This invention relates to mailing wrappers, particularly such as are suitable for mailing photographs, magazines, books or similar articles which must be mailed flat.

The principal object of this invention is to provide a mailing wrapper of this character in which the flaps may be readily and securely fastened, avoiding the possibility of accidental unfastening.

Another object is to provide a wrapper which may readily be opened without tearing the flaps.

A further object is to provide a construction whereby the side and end flaps are readily interlocked and also as readily unlocked from each other.

Still further objects and advantages will appear more fully from the detailed description and the features of novelty will be particularly pointed out in the claims.

Referring to the drawings illustrating this invention, Figure 1 is a perspective view of my improved wrapper, showing one of the fasteners in locked and the other in unlocked position. Fig. 2 is a development on a reduced scale of the construction illustrated in

Fig. 1. Figs. 3 and 4 are respectively a plan view and a development of a modified form showing the projecting ends of the flaps formed with inclined edges. Figs. 5 and 6 are respectively a plan view and a develop-

ment of a form in which the projecting ends of the flaps are formed with inwardly inclined edges in an opposite direction from the form illustrated in Figs. 3 and 4. Figs. 7 and 8 are respectively a plan view and a development of a modified form in which the flaps are each formed with a plurality of notches. Figs. 9 and 10 are perspective views illustrating a further modified form of box which can be made of a stiff material such

as corrugated board or the like. The invention is more particularly adapted for a wrapper which when set up forms a box-like construction, the entire wrapper being preferably of a single piece of comparatively stiff though somewhat flexible

material such as pasteboard or the like. The wrapper accordingly consists of a bottom portion, side portions constituting walls and side and end flaps extending from the walls. These side flaps are preferably formed with notches at their adjacent edges dividing the flaps into a plurality of sections which respectively overlie and underlie one another resulting in an interlocked construction when the box is set up. The ends of each of the flap sections are formed with projections which are held down to the end flaps underlying the side flaps by means of suitable fasteners which are preferably attached to the end flaps and adapted to be turned over these end projections.

Referring in detail to the drawings, particularly to Figs. 1 and 2, the wrapper consists of a bottom 10, side walls 11 and 12 having side flaps 13 and 14 forming a continuation thereof, end walls 15 and 16, and end flaps 17 and 18 forming a continuation of the end walls. The side flaps 13 and 14 are formed preferably with V shaped notches 19 and 20, dividing the flaps into sections 21 and 22, and 23 and 24. When the box is set up, the meeting flaps 13 and 14 are interlocked by interengagement at their notches 19 and 20, the flap sections of the opposing flaps overlapping each other as clearly illustrated in Fig. 1. The notches are preferably cut to a depth such that the apices of the notches register and abut when the flaps are so interlocked.

To further secure the side flaps to each other and also to interlock with the end flaps, I form the ends of the flap sections 21, 22, 23 and 24 with projecting portions 25, 26, 27 and 28 registering over one another and attach these projecting portions to the end flaps. Preferably, the fastening means consists of a strip of sheet metal 29 secured to each of the end flaps 17 and 18 in any suitable manner, as by tongues 30 which extend through slits formed in the flaps. The strip has end portions 31 which are positioned so that they can be bent over the projecting ends 25, 26, 27 and 28 as illustrated at the top of Fig. 1, in connection with the flap 17. When these end portions 31 are so bent over, the ends 25, 26, 27 and 28, of the side flaps are locked to each other and also to the end flaps, thus securely fastening the parts together. The end portions 31 are preferably formed with inclined

edges 32, fitting the inclined edges 33 of the end edges of the side flaps, and also lying closely adjacent to the apices of the notches formed by the projections 25, 26, 27, 28 and the inclined edges 33. In this way, longitudinal motion of the flaps relatively to each other is effectually prevented.

In the modified constructions illustrated in Figs. 3 and 4, the projections 25^a, 26^a, etc., 10 of the side flaps are formed with outwardly inclined side walls 50 over which are turned the end portions 31^a of the fasteners. These fasteners may be formed with an inclined notch, score, or perforation 51 corresponding to the inclination of the walls 50, thus causing the end portions 31 to properly bend over these walls. The fasteners 29^a may be formed with extensions 52 which extend over the end walls 15^a and 16^a and are fastened 15 on the bottom portion in a suitable manner as by tongues 53. In this way, the end walls are strengthened by the extensions 52 which constitute metallic struts resisting compression. It will be noted that these fasteners 25 are longer than the fasteners 29 in the form 20 illustrated in Figs. 1 and 2, and thus may further strengthen and stiffen the end flaps and thereby the entire face of the wrapper.

In the form illustrated in Figs. 5 and 6, 30 the end portions 25^b and 26^b of the side flaps are formed with inwardly inclined walls 60 over which the end portion 31^b of the metallic fasteners are bent, thus resisting an inward pull upon the flaps as well as an outward pull. The fasteners 29^b are also formed with projections 61 which may be turned over to strengthen the corners.

In the form illustrated in Figs. 7 and 8, 35 the side flaps 13^c and 14^c are each formed with a plurality of notches 19^c and 20^c. These notches are preferably not quite so deep as the notches used in constructions illustrated in Figs. 1 to 4. In other respects the construction is similar to these figures.

40 In Figs. 9 and 10, a modified construction is illustrated which is adapted for use in connection with a wrapper or box of a stiffer material such as corrugated board, etc. The flaps 13^d and 14^d when folded over into 45 closed position abut each other and are formed with end projections 25^d and 26^d which respectively abut the end projections 27^d and 28^d of the opposed flap. The fasteners 29^d are formed with the end projections 55 31^d which may be bent over the projections 25^d, 27^d, etc., and also with a side projection or tongue 70 which may be turned over the meeting edges of the abutting projecting portions. In this way, the flaps are securely 60 held in position.

From the various forms of my invention above described, it will be seen that I have provided a mailing wrapper in which the side flaps are interlocked with each other 65 and also with the end flaps by the same fas-

teners to securely hold the wrapper when it is fastened for shipment. Although the wrapper is thus securely held, it is still readily fastened and unfastened, the fastening pieces in some cases not only holding the flaps but also strengthening and bracing the wrapper itself. 70

Having thus described my invention, I claim—

1. A wrapper having a body portion, end flaps, and meeting side flaps extending over the end flaps, said side flaps being formed with registering projections and fasteners attached to the end flaps adapted to engage the projections to hold the side flaps firmly 75 to the end flaps. 80

2. A wrapper having end and side walls, end flaps and side flaps extending from the respective walls, said side flaps being formed with registering projections, and fasteners 85 attached to the end flaps adapted to engage the projections to hold the side flaps firmly to the end flaps. 90

3. A wrapper having a body portion, end flaps, and meeting interlocking side flaps extending over the end flaps, said side flaps being formed with registering projections and fasteners attached to the end flaps adapted to engage the projections to hold the side flaps firmly 95 to the end flaps. 100

4. A wrapper having walls, opposed flaps extending from said walls, one pair of said flaps interlocking with each other and formed with registering projections at their ends, and fasteners attached to the other of the flaps and engaging said end 105 projections. 110

5. A wrapper comprising a bottom portion, two pairs of opposed flaps extending therefrom, the meeting edges of one pair of 115 said flaps having registering notches dividing the flaps into a plurality of interlocking sections, said interlocking flaps being formed with registering end projections, and fasteners attached to the other pair of flaps for retaining said projections. 120

6. A wrapper having walls, two pairs of opposed flaps extending from said walls, one of these pairs of flaps having notches at their ends forming registering projections, 115 and fasteners attached to the other pair of flaps and projecting into the apices of the notches to form abutments therefor and adapted to be turned over to engage the projections. 125

7. A wrapper having walls, two pairs of opposed flaps extending from said walls, one of these pairs being formed at their ends with notches having inclined edges forming registering projections, fasteners attached to 125 the other pair of flaps and projecting into the apices of the notches to form abutments therefor and adapted to be turned over to engage the projections, the fasteners having inclined edges to register with the inclined 130

edges of the notches so as to be freely movable into position for engaging the projections.

8. A wrapper having walls, two pairs of opposed flaps projecting from said walls, one pair of said flaps having registering notches dividing these flaps into a plurality of interlocking sections, the ends of these flaps having notches to form end projections overlying one another, and fastening means attached to the other pair of flaps adapted to be turned over said end projections and to retain the same together with their flaps in position when the wrapper is closed.
- 15 9. A mailing wrapper having walls, two pairs of opposed flaps projecting from said walls, one pair of said flaps having registering notches dividing these flaps into a plurality of interlocking sections, the ends of the flaps having notches to form end projections, and fastening means attached to the other pair of said flaps adapted to engage the end projections, said fastening means

having a portion thereof extending over the walls and serving to strengthen the same. 25

10. A wrapper having a bottom, end and side walls, two pairs of opposed flaps projecting from said walls, one pair of said flaps having registering notches dividing these flaps into a plurality of interlocking sections, the ends of the flaps having notches to form end projections, fastening means attached to the other pair of said flaps adapted to engage the end projections, said fastening means having a portion thereof extending over the walls, and an extension therefrom adapted to be fastened to the bottom of the wrapper. 30 35

Signed at New York city, in the county of New York, and State of New York, this 40 12th day of April, A. D. 1913.
